UNITED STATES PATENT OFFICE.

HARRY S. SMILA, OF NORTH BALTIMORE, OHIO.

DESIGN FOR A SEAL.

SPECIFICATION forming part of Design No. 28,538, dated May 3, 1898.

Application filed February 23, 1898. Serial No. 671,392. Term of patent 7 years.

To all whom it may concern:

Be it known that I, HARRY SYLVANOUS SMILA, a citizen of the United States, residing at North Baltimore, in the county of Wood and State of Ohio, have invented and produced a certain new and original Design for Seals; and I do declare the following to be a full, clear, and exact description of the invention, such as will enable others skilled in the art to which it appertains to make and use the same.

My invention relates to a new and original design for seals; and it consists of a seal of the configuration shown in the accompanying drawings, in which—

Figure 1 is a side elevation of the seal, and Fig. 2 is a longitudinal sectional view.

The leading feature of my invention consists in a thin strip of material having rectangular ends A, from the inner sides of which project conical extensions B, that are connected by a circular head D.

What I claim is—

The design for a seal, as herein shown and described.

In testimony whereof I have hereunto set my hand in presence of two subscribing witnesses.

H. S. SMILA.
